UNITED STATES PATENT OFFICE

ADOLPH L. NELSON, OF DETROIT, MICHIGAN, ASSIGNOR TO BOHN ALUMINUM & BRASS CORPORATION, OF DETROIT, MICHIGAN

CLAMP

Application filed June 15, 1925. Serial No. 37,316.

The invention relates to clamps and is particularly applicable to permanent molds which are exposed to heat. One of the objects of the invention is to provide a construction of clamp which is long-lived by reason of the fact that the cooperating clamping members have a rolling contact with each other instead of a sliding contact. Another object is to provide a clamp, the clamping members of which are relatively adjustable to retain the sections to be clamped in different positions or to release these sections. With these as well as other objects in view the invention resides in the novel features of construction and combinations and arrangements of parts as more fully hereinafter set forth.

In the drawings:

Figure 1 is an end view of a permanent mold having a clamp embodying my invention;

Figure 2 is a plan view thereof partly in section on the line 2—2 of Figure 1.

As shown in the present instance 1 and 2 are complementary sections of the permanent mold, the ends of which are pivotally connected to each other at 3. 4 is a core insertable downwardly between the sections 1 and 2 and cooperating therewith in forming the mold cavity. The mold sections in addition to being exposed to the heat of the molten metal entering the mold cavity are also preferably exposed to the heat of gas or the like flames directed against the mold sections.

To clamp the mold sections together I have provided the clamping member 5 and the cooperating clamping member 6, which are located at the end of the mold opposite its pivotal end. One end of the clamping member 5 is pivotally connected between the spaced furcations 7 projecting laterally from the mold section 1 by means of the pin 8 extending through the furcations and the laterally enlarged portion 9 of the clamping member. The opposite end of the clamping member 5 is provided with the laterally hooked portion 10, which is engageable between the spaced furcations 11 projecting laterally from the mold section 2. The cooperating clamping member 6 is in the form of a pin 12 having at

its upper end the transverse handle 13. This pin is insertable downwardly through the furcations 11 and has cylindrical bearing portions 14 for engaging these furcations and the intermediate cam portion 15 for engaging the shoulder 16 upon the hooked portion 10 of the clamping member 5. This cam portion 15 preferably has the diverging flat sides 17 and 18 which are so arranged relative to the shoulder 16 of the clamping member 5 that when the latter is in clamping position clearance is provided between this shoulder and the flat sides. However, the mold sections 1 and 2 cannot be entirely separated but can be slightly separated a sufficient distance to permit convenient insertion of the core 4 from between the mold sections. The cam portion 15 also has the cam surface 19 leading from the flat face 18 and arranged so that when the cooperating clamping member 6 is rotated the cam face will have a rolling contact with the shoulder 16 of the clamping member 5, and will gradually, during the rotation, move the mold sections toward each other and finally clamp the same firmly together.

To provide for the ready removal of the clamp and the renewal of its parts there is slight clearance between the pin 8 and the furcations 7 and clamping member 5. There is also slight clearance between the cylindrical bearing portions 14 of the cooperating clamping members 6 and the furcations 11. Also the cam portion 15 of this cooperating clamping member is reduced so that it does not contact with the furcations 11. The pin 8 and the cooperating clamping member 6 are suitably held from dropping through their respective furcations by means of a head upon the pin and a transverse pin below the cooperating clamping member.

With this arrangement it will be seen that even with the cooperating clamping members at high temperature they will work efficiently and have a long life owing to the rolling contact therebetween. It will also be seen that they are so arranged that the mold sections may be clamped either firmly together or slightly spaced apart.

What I claim as my invention is:

The combination with relatively movable sections, of a clamping member connected to one of said sections, and a cooperating clamping member rotatively mounted upon the other of said sections and provided with a cam portion having a flat face and a cam face alternatively engageable with said first mentioned clamping member to clamp said sections in different positions, said cam face being arranged to provide a rolling contact with said first mentioned clamping member.

In testimony whereof I affix my signature.

ADOLPH L. NELSON.
